SLOT-GATE FOUNDRY MOLD

Ralph C. Hawk, Bay County, and John G. Mezoff, Bay City, Mich., assignors to The Dow Chemical Company, Midland, Mich., a corporation of Delaware

Application June 13, 1946, Serial No. 676,380

1 Claim. (Cl. 22—134)

1 This invention relates to improvements in bottom-pour slot-gate molds and in foundry procedures for casting metal in such molds.

In making castings of many types, it is desirable that the molten metal be introduced into the foundry mold in such manner that the casting solidifies progressively from the bottom upward. In this way, each portion of the casting as it freezes is overlain with molten metal, and shrinkage flaws and porosity are largely avoided.

One means of achieving upward solidification which has been recommended is the slot-gate mold, sometimes termed slit-gate or knife-gate mold. In this construction, a deep inlet well is formed in the mold adjacent to the casting cavity and is connected to the latter by a narrow vertical slot which usually extends the full depth of the cavity. The metal to be cast is introduced into the well and from there passes through the slot into the cavity. It is intended that the metal flow wholly within the well until it reaches a level corresponding to that of the metal already in the casting cavity and then flow gently through the slot-gate horizontally into the cavity, thus entering on top of earlier poured metal. In this way the newly added and hottest metal should always be at the highest point in the mold, so that upward freezing will be assured.

In practice, slot-gate molds of types heretofore known have been only partially effective in operating in the desired manner. In most instances, the metal being poured, instead of first flowing in the well to the prevailing metal level and thence into the cavity, tends to cut through the slot below the metal level and stream upward within the casting cavity, upsetting the thermal balance. This effect has been particularly pronounced in bottom-pour slot-gate molds, in which the metal enters the well from below (British Patent 408,153), because the upper parts of the well are comparatively cold and retard flow, whereas the submerged parts of the slot are hot and offer no such resistance.

With these considerations in mind, it is the principal object of the present invention to provide an improved slot-gate mold construction which in actuality achieves in large measure the desirable flow path for the metal being poured which has been intended in prior slot-gate molds. Another object is to provide a mold which is particularly adapted to the founding of magnesium-base alloys and permits pouring sound heavy castings with in general less rigging than has been required heretofore. An additional object is to provide an improved procedure for filling slot-gate molds.

These objects are realized in the invention by positive means associated with the inlet well of the mold for insuring that the effective level at which the metal being poured passes through the

2 slot-gate into the casting cavity is neither materially above nor below the level of the metal already in the cavity. These means may include a restricted orifice for controlling the entry of metal into the well, and a perforated baffle for controlling the movement of metal from the well into the casting cavity.

As is known, the metal being introduced into the well of a bottom-pour slot-gate mold should preferably enter at the bottom center as a stream flowing vertically upward and having a cross-sectional area small relative to that of the well. In this way, whatever jet action the stream may possess tends to convey the entering metal within the well to the prevailing metal level with minimum side-flow through submerged parts of the slot-gate. In the invention, this desirable flow is insured by providing at the bottom center of the well a restricted inlet orifice connecting the well with the sprue and runner through which the metal is poured, the orifice having an area small in comparison to that of the well, i. e. having a diameter which is a minor fraction of that of the well. In addition to furnishing a stream of the requisite small area, the orifice also acts as a choke to maintain the rate of flow relatively constant, eliminating the need for extreme care in the pouring.

In the slot-gate molds of the invention, it is also desirable to place a screen or other multiply-perforated baffle in the well and covering the entrance to the slot-gate. A major purpose of such a screen is to stabilize the flow of metal from the well into the casting cavity. By momentarily retarding the metal and requiring to pass through a large number of small openings, the screen effectively reduces eddying and vertical motion in the stream, permitting quiet flow into the casting cavity. The screen may also function as something of a guide, impeding sidewise flow through the slot-gate below the prevailing metal level in the mold. While simple sheet screens or multiply-perforated plates may be employed, preferred construction calls for a tubular screen centered in the well and extending its full depth, the screen having a cross-sectional area which materially exceeds that of the inlet orifice, e. g. having a diameter which is a major fraction of that of the well.

In the founding of readily-oxidizable metals, such as magnesium-base alloys, the screen performs the additional function of skimming unavoidable oxide inclusions from the metal as it enters the casting cavity. Unlike screens used heretofore, a screen within the inlet well has the advantage that, since the metal level is constantly rising during pouring, a fresh screen surface is continually presented to the metal. A further advantage of the screen according to the invention is that possible plugging by the oxide

filtered out takes place from the bottom of the well upward, and this plugging assists in restraining flow of entering metal into the casting cavity at levels below that prevailing in the well.

Some further advantage may be realized, according to the invention, by placing a guide wire such as a strand of steel wool in the well of a bottom-pour slot-gate mold to smooth out the flow of metal.

While the bottom inlet orifice, screen, and guide wire as described are individually helpful in establishing the desirable flow path of metal entering a slot-gate mold, molds including combinations of these elements are especially effective. A particularly desirable construction, which illustrates a preferred embodiment of the invention, is shown in the accompanying drawing, in which

Fig. 1 is a fragmentary vertical section of a bottom-pour slot-gate mold, taken along the line 1—1 of Fig. 2, and

Fig. 2 is a horizontal section of the mold, along the line 2—2 of Fig. 1.

The mold shown in the drawing is a conventional two-part mold of rammed foundry sand defining a casting cavity 4. An open-top vertical well 5 is formed in the mold adjacent to the casting cavity and extending the full depth thereof, with a slot-gate 6 connecting the well with the cavity. The mold is filled through a pouring cup 7 and sprue 8 from which a runner 9 leads to a point beneath the well 5. Inset in the mold at the bottom of the well is an orifice core 10 provided with a vertical opening 11 connecting the bottom center of the well with the runner, the diameter of the opening being a minor fraction of that of the well and being materially less than that of the sprue. Centered in the well 5 is a tubular screen 12 made of sheet iron having a very large number of closely-spaced small perforations, or of woven wire fabric, and rolled and crimped into a tube of diameter more than half that of the well. The screen is steadied at its upper end by a rammed-sand ring 13 resting on the top of the mold. A strand of steel wool 14 is centered axially in the well, being tucked under the screen at the bottom.

In using the mold of Figs. 1 and 2, the molten metal to be cast is poured into the cup 7 at a rate sufficient to keep it nearly full. The metal flows through the sprue 8, runner 9 and the inlet 11 as a stream of constant rate and rises inside the screen 12. On reaching the level of metal in the mold, the stream spreads out horizontally without turbulence and flows gently through the

screen 12 and slot-gate 6 into the casting cavity 4.

While the invention has been described with reference to an inlet well having a single slot-gate, it is equally possible to have two or more slot-gates opening from a single well and leading to the same or different casting cavities. It will also be appreciated that the principles of this invention are applicable in plaster and in permanent-mold casting as in sand-casting.

The foregoing description is illustrative rather than strictly limitative, there being many possible variations of the construction described within the scope of the following claim.

Attention is directed to our co-pending application Serial No. 676,379, filed June 13, 1946, in which there is claimed a top-inlet slot-gate foundry mold assembly embodying some of the same principles as the present invention.

What is claimed is:

A foundry mold having a casting cavity, a vertical inlet well adjacent to the cavity, a slot-gate connecting the cavity with the well, a sprue in communication with the well through a central bottom inlet in the well having a diameter which is a minor fraction of that of the well, a tubular screen having a diameter which is a major fraction of that of the well centered in the well and extending the full height thereof, and a strand of steel wool centered axially within the screen and extending the full height thereof.
